UNITED STATES PATENT OFFICE.

GEORGE S. JONES, OF INDIANAPOLIS, INDIANA.

DESIGN FOR A FONT OF TYPE FOR USE IN PHONETIC SPELLING.

No. 38,617.

Specification for Design.

Patented June 11, 1907.

Application filed May 18, 1907. Serial No. 373,519. Term of patent 14 years.

To all whom it may concern:

Be it known that I, GEORGE S. JONES, a citizen of the United States, residing at Indianapolis, in the county of Marion and State of Indiana, have invented a new, original, and ornamental Design for a Font of Type for Use in Phonetic Spelling, of which the following is a specification, reference being had to the accompanying drawing, forming part thereof.

The figure is a plan view of a font of type for use in phonetic spelling showing my new design.

I claim:

The ornamental design for a font of type for use in phonetic spelling, as shown.

GEORGE S. JONES. [L. S.]
